UNITED STATES PATENT OFFICE.

GEORGE W. PRENTICE, OF PROVIDENCE, RHODE ISLAND.

BUTTON-FASTENER.

SPECIFICATION forming part of Letters Patent No. 293,910, dated February 19, 1884.

Application filed December 31, 1883. (No model.)

To all whom it may concern:

Be it known that I, GEORGE W. PRENTICE, a citizen of the United States, and a resident of Providence, in the county of Providence and State of Rhode Island, have invented an Improvement in Button-Fasteners, of which the following description, in connection with the accompanying drawings, is a specification, like letters on the drawings representing like parts.

This invention relates to that class of button-fasteners having a base or table and several prongs bent at right angles thereto, and in which the shank-eye of a button engages one of said prongs, which is usually termed the "button-prong," while the others are referred to as the "holding-prongs," the several prongs being caused to penetrate and be clinched to the shoe or fabric, to secure the button in place.

In the manufacture of such button-fasteners it is found that because of the thinness of the metal sheet or stock from which said fasteners are formed, and the sharp bend given to the holding-prongs, to dispose them in a plane at right angles to the table, the metal cracks at the point of bend in said prongs, thereby materially weakening the fasteners and rendering them, in many instances, unfit for use. More especially is this the case when the metal stock is somewhat "short" or brittle. Such weakened portions of the fastener are additionally weakened in resisting the strain put upon them when the ends of the holding-prongs are swaged or tapered to a point to adapt them to readily penetrate the material to which the fastener is to be secured.

The object of my invention is to provide a strong reliable button-fastener, which, when adapted for use, shall not have the defects hereinbefore mentioned, and which shall require in its manufacture but a small additional quantity of metal disposed where it is most required.

To this end my invention consists of a button-fastener having a table and a button-carrying prong, and two or more holding-prongs bent at right angles to the table and integral therewith, with the button-carrying prong of thinner metal than the other prongs, substantially as hereinafter described, and particularly pointed out in the claims.

Figure 1 is a perspective view of my improved button-fastener; Fig. 2, a perspective view of the blank from which the fastener is formed, presenting the reverse or under surface to view; Fig. 3, a perspective view of a sheet-metal strip from which the blanks are cut, said strip showing a blank cut therefrom; Fig. 4, a transverse section thereof on line xx of Fig. 3; and Fig. 5 shows a modification of my improved button-fastener.

In the present instance my improved button-fastener consists of a table, a , a button-carrying prong, b , projecting from one side or edge of the table, and two substantially-parallel holding-prongs, b' , projecting from the opposite side or edge of said table, the whole formed in one piece from the blank shown in Fig. 2, by bending the holding-prongs b at right angles to the table, and, by forming an eye or staple, c , in the button-prong near its heel, and bending said prong in the usual manner. The blank from which the fastener is formed is cut from a sheet-metal strip, whose thickness varies in cross-section, substantially as shown in Fig. 4, whereby the button-prong b and the central portion of the table a are formed from the thinner or central portion of the strip, and the holding-prongs b' and the outer portion of said table are formed from the thicker or outer portions of said strip. By this formation of parts the holding-prongs are materially strengthened at the point of bend, to prevent cracking or injury to the metal when they are being bent; and, further, the bends in said holding-prongs b' will not be so sharp as heretofore, but will be more gradual or rounding, because of the additional thickness of metal at such points. Again, the table contiguous to the bends in the holding-prongs is strengthened, which is a desirable feature, and the increase of metal in the holding-prongs, more especially at the point of bend, permits a true taper to be given to said prongs from the point of bend to the ends thereof, for the reason that the metal at the bend of the holding-prongs is able to resist the strain put upon it when the prongs are being swaged or tapered, in the course of manufacture, to sharpen them, and thus adapt the said prongs to easily penetrate the fabric or shoe to which the button is to be secured. Thus formed my improved button-fastener is

made strong and durable without materially increasing its bulk or rendering it heavy or clumsy at points where it should be lightly and neatly made.

5 As shown in the modification, Fig. 5, the form or configuration of my button-fastener may be changed or modified to a considerable extent and yet retain the essential feature of my invention.

10 It will be noticed that while the table is composed of metal of varying thickness the face of said table, or that portion presented to view when the fastener is secured to a shoe or fabric to hold a button thereon, presents a 15 plane surface, as in the ordinary fastener, while the under surface, or that portion which is brought in contact with the material, is uneven, or what might be termed "corrugated."

When the fastener is securely clinched to 20 the material, the said material, because of its yielding quality, is made to conform to the irregular or uneven under surface of the fastener, which thereby tends to hold said fastener more firmly in place.

25 What I claim is—

1. An improved one-piece sheet-metal button-fastener, consisting of a table and several prongs, bent at an angle thereto, with one of said prongs of thinner metal than the remaining prongs, and adapted to carry a button, for 30 the purpose set forth.

2. An improved one-piece sheet-metal but-

ton-fastener, consisting of a table having different thicknesses of metal, and several prongs projecting from said table and bent at an angle thereto, with one of said prongs of the thickness corresponding to the thinnest portion of the table, and adapted to engage the shank-eye of a button, for the purpose set forth. 35

3. A button-fastener consisting, essentially, 40 of a table having a plane upper surface and an uneven or corrugated under surface, and provided with several prongs integral therewith and bent at an angle thereto, and one of said prongs adapted to engage the shank-eye 45 of a button, for the purpose set forth.

4. The herein-described button-fastener, consisting, essentially, of a table the metal of which varies in thickness, and a button-prong and two holding-prongs, the said button and 50 holding-prongs projecting from opposite sides of the table and bent at an angle thereto, with the button-prong of a thickness corresponding to the thinnest portion of the table, and the holding-prongs corresponding in thickness 55 to the thickest portion of the said table, all as set forth, and for the purpose specified.

In testimony whereof I have signed my name to this specification in the presence of two subscribing witnesses.

GEORGE W. PRENTICE.
